UNITED STATES PATENT OFFICE.

OTTO W. SCHAUM, OF PHILADELPHIA, PENNSYLVANIA.

DESIGN FOR AN ARM MEMBER FOR JACQUARD-LEVERS.

SPECIFICATION forming part of Design No. 33,296, dated October 2, 1900.

Application filed August 31, 1900. Serial No. 28,716. Term of patent 14 years.

To all whom it may concern:

Be it known that I, OTTO W. SCHAUM, a citizen of the United States, residing in the city and county of Philadelphia, and State of Pennsylvania, have invented a new and original Design for an Arm Member of a Jacquard-Lever; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

In the accompanying drawings, wherein like letters of reference designate corresponding parts, I have fully illustrated my invention.

In said drawings, Figure 1 is a view in side elevation of the arm member of a jacquard-lever formed in accordance with my invention. Fig. 2 is a top plan view of said arm member, and Fig. 3 is an enlarged transverse sectional view on the line xx in Fig. 2.

The essential or salient feature of my design consists in an arm member for a jacquard-lever having one end plain or flat, the other end bent downwardly and terminating in a bearing-head and having its intermediate portion provided with side flanges or ribs. Said arm member consists of a bar which in elevation appears perfectly straight, but which in side view is seen as having its end portion a bent downwardly. The other end portion b of said bar is perfectly flat, its

extremity appearing rounded in side elevation, as at c . The flattened end portion b of the member is thicker than the body portion d thereof. The rear end portion of the member terminates in a bearing-head e , which comprises an integral enlargement f on the end of said member and a separable plate g , said enlargement and the plate having corresponding ears h , penetrated by bolts i . The bearing-head is of greater thickness than the flattened end portion b and is pierced by a bore i' .

On the sides of the body portion d of the member are centrally-disposed longitudinally-extending flanges or ribs j , which, as seen in elevation, Fig. 2, appear to taper toward the end portion b of the member, being at their greatest width approximately as thick as the bearing-head. Adjacent the end portion a in the member it is formed with two laterally-extending ears k , each of which is penetrated by an orifice l .

Having thus fully described my invention, what I claim as new, and desire to secure by Letters Patent, is—

The design for the arm member of a jacquard-lever, substantially as herein shown and described.

In testimony that I claim the foregoing I have hereunto set my hand this 29th day of August, 1900.

OTTO W. SCHAUM.
